UNITED STATES PATENT OFFICE.

ROBERT J. HEWETT, OF WESTFIELD, NEW JERSEY.

RAILWAY SIGNAL SYSTEM.

Application filed February 19, 1923. Serial No. 619,363.

To all whom it may concern:

Be it known that I, ROBERT J. HEWETT, a citizen of the United States, residing at Westfield, in the county of Union and State 5 of New Jersey, have invented certain new and useful Improvements in Railway Signal Systems, of which the following is a full, clear, and exact description.

This invention relates to railway signal systems with which traffic in both directions over a stretch of single track between two passing stations may be governed. An object of the invention is to provide an improved signal system with which both absolute and permissive control of traffic may be obtained in an exceedingly simple, safe and efficient manner with a minimum of circuits, relays and other parts. A further object is to provide an improved system with 10 which the presence of a train at any point in a part or all of the stretch of single track may be indicated at one of the passing tracks, and which may be employed in connection with signals governing traffic in 15 both directions without the necessity of utilizing additional relays. A further object is to provide an improved signal system which the operation of the switch at the junction of the stretch of single track 20 with one of the passing tracks, for the purpose of connecting the main track with the passing track, will automatically set the signals along the stretch of single track to govern the movement of a train entering the 25 stretch of single track from the passing track through the operated switch, and which will permit a switching movement against opposing traffic. Other objects and advantages will be apparent from the 30 following description of an embodiment of the invention and the novel features will be particularly pointed out hereinafter in claims.

In the accompanying drawings:

Figures 1 and 2 taken together, illustrate 45 diagrammatically a stretch of single track connecting two passing stations, including the signal controlling circuits with the signals at clear;

Figures 3 and 4 taken together, illustrate 50 the same stretch of track with a train about to enter the stretch of single track and with the signals set to permit this movement of the train;

Figures 5 and 6 taken together, illustrate the same with the train partly through the 55 stretch of track;

Figures 7 and 8 taken together, illustrate the same with a train at a different point in its travel between the passing stations; 60

Figures 9 and 10 taken together, illustrate the same with an indicator providing for switching movements against the opposing traffic.

Reference may now be had particularly to Figs. 1 and 2 which taken together illustrate a stretch of single track between two passing stations, in which the control circuits are in normal condition. At the left of Fig. 1 is shown a typical double or passing track junction in which west bound signal 111 controls west bound traffic over the west bound main track, of which track section T¹¹¹ and track relay R¹¹¹ form a part. East bound absolute signal 110 controls east bound traffic from the east bound main track to the single track. The east bound main track is connected to the single track by means of the switch S¹¹⁰ which is normally open as shown. That is, the switch is normally set for a west bound train movement from the single track to the west bound main track of the double track section. 70

The track circuits and track relays are arranged in the usual way. At east bound absolute signal 110, track relay R¹¹⁰ is connected to track section T¹¹⁰. At west bound signal 113, track relay R¹¹³ is connected to track section T¹¹³. Each track section T¹¹⁰ and T¹¹³ is provided with a track battery at their intermediate insulated joints, as shown. Two track sections for each sub-block are shown. One track section only, or any number of track sections may be used. 75

At the right of Fig. 2 is shown a similar double or passing track junction in which east bound signal 116 controls east bound traffic over the east bound main track, of which track section T¹¹⁶ and track relay R¹¹⁶ form a part. West bound absolute signal 117 controls west bound traffic from the west bound main track to the single track. West bound main track is connected to the single track by means of the switch S¹¹⁷ which is normally open as shown. That is, the switch is normally set for an east bound 80

train movement from the single track to the east bound main track of the double track section.

In Figs. 1 and 2 the control circuits and signals are shown in their normal clear condition. In Fig. 1 the control circuit for east bound absolute signal 110 is as follows:—From line relay L^{110} , wire 1, contact 2 of track relay R^{110} , line wire 3, contact 4 of track relay R^{113} , wire 5, wire 6, absolute contact 7 of east bound line relay L^{112} , wires 8, 9, positive pole chamber P, positive wires p, p, battery B^{112} , negative wire n, negative pole chamber N and common wire C back to the common terminal of line relay L^{110} , at signal 110. Contact 7 of east bound line relay L^{112} provides the through or absolute control for east bound absolute signal 110. The permissive control for east bound absolute signal 110 is provided by back contact 11 of west bound line relay L^{113} and is as follows: From contact 4 of track relay R^{113} , wire 5, wire 10, back contact 11 of west bound line relay L^{113} when deenergized, wire 12, circuit controller 13 operated by west bound signal 113 and closed when said signal is in its stop position, wire 14, wire 9, positive pole changer P, positive wires p, p, battery B^{112} , negative wire n, and negative pole changer N to the common wire C.

The control circuit for east bound signal 112 is similar and is as follows:—In Fig. 1 from east bound line relay L^{112} , wire 1, contact 2 of track relay R^{112} , line wire 3, in Fig. 2, line wire 3, contact 4 of track relay R^{115} , wire 5, wire 6, absolute contact 7 of east bound line relay L^{114} , wires 8, 9, positive pole changer P, positive wires p, p, battery B^{114} , negative wire n, negative pole changer N to common wire C. The permissive control is from contact 4 of track relay R^{115} , wire 5, wire 10, back contact 11, of west bound line relay L^{115} , wire 12, circuit controller 13 when closed, wire 14, wire 9, positive pole changer P, positive wires p, p, battery B^{114} , negative wire n, negative pole changer N to common wire C.

The control circuit for east bound signal 114 is as follows: From east bound line relay L^{114} , wire 1, contact 2 of track relay R^{114} , line wire 3, contact 4 of track relay R^{117} , wire 5, normally closed circuit controller 6 operated by switch S^{117} of west bound main track T^{117} F, wire 7, positive pole changer P, positive wires p, p, battery B^{116} , negative wire n, negative pole changer N and common wire C back to east bound line relay L^{114} at east bound signal 114. East bound signal 114 being the last intermediate signal in the road block is not controlled by east bound line relay L^{116} of east bound main track section T^{116} . It is, however, controlled by circuit controller 6 of switch S^{117} of west bound main track section T^{117} F, the purpose of which is to set the

route west bound for a west bound train when about to enter the single track section at signal 117.

The control circuits for the west bound signals are similar and are designated by another set of numerals. The control circuit for west bound absolute signal 117 is as follows:—From line relay L^{117} , wire 31, contact 32 of track relay R^{117} , line wire 33, contact 34 of track relay R^{111} , wire 35, wire 36, absolute contact 37 of west bound line relay L^{115} , wire 38, 39, positive pole changer P, positive wires p, p, battery B^{115} , negative wire n, negative pole changer N, and common wire C back to the common terminal of west bound line relay L^{117} at signal 117. Contact 37 of west bound line relay L^{115} provides the through or absolute control for west bound absolute signal 117. The permissive control for west bound absolute signal 117 is provided by back contact 41 of east bound line relay L^{114} and is as follows: From contact 34 of track relay R^{114} , wire 35, wire 40, back contact 41, of east bound line relay L^{114} , when deenergized, wire 42, circuit controller 43 operated by east bound signal 114 and closed when said signal is at stop, wire 44, wire 39, positive pole changer P, positive wires p, p, battery B^{115} , negative wire n, negative pole changer N and common wire C back to line relay L^{117} at absolute signal 117.

The control circuit for west bound signal 115 is as follows: In Fig. 2 from west bound line relay L^{115} , wire 31, contact 32 of track relay R^{115} , line wire 33; in Fig. 1, line wire 33, contact 34, of track relay R^{112} , wire 35, wire 36, absolute contact 37 of west bound line relay L^{113} , wires 38, 39, positive pole changer P, positive wires p, p, battery B^{113} , negative wire n, negative pole changer N and common wire C back to line relay L^{115} at signal 115.

The permissive control for west bound signal 115 is as follows: In Fig. 1 at east bound signal 112, from contact 34 of track relay R^{112} , wire 35, wire 40, back contact 41 of east bound line relay L^{112} , when closed, wire 42, circuit controller 43, closed when signal 112 is at stop, wire 44, wire 39, positive pole changer P, positive wires p, p, battery B^{113} , negative wire n, negative pole changer N and common wire C back to west bound line relay L^{115} in Fig. 2. The back contact 41 operates as the dominating permissive control and the circuit controller 43 provides the safety factor for mechanically operated signals which insures proper operation of the signal before the permissive circuit is rendered effective, where light signal systems are used the mechanically operated circuit controllers for the permissive circuit may be omitted.

From the foregoing it is seen that the absolute control is provided by the absolute

control contact on each intermediate line relay in the usual way. The permissive control is provided by the back contact on the companion line relay for the opposite direction and is effective in advance of a train in the running direction. The absolute control and also the permissive control are both provided for by the same line relay. This permissive control by the back contact of the opposite line relay is one of the new and novel features of my invention.

The control circuit for west bound signal 113 is as follows: From west bound line relay L^{113} , wire 31, contact 32 of track relay R^{113} , line wire 33, contact 34 of track relay R^{110} , wire 35, circuit controller 36 operated by switch S^{110} of east bound main track section T^{110} F, wire 37, positive pole changer P, positive wires p, p , battery B^{111} , negative wire n , negative pole changer N, and common wire C back to the common side of west bound line relay L^{113} at signal 113. West bound signal 113 being the last intermediate signal in the road block is not controlled by west bound line relay L^{111} of west bound main track section T^{111} . It is, however, controlled by circuit controller 36 of switch S^{110} of east bound main track section T^{110} F, the purpose of which is to set the route east bound for an east bound train about to enter the single track section.

The line control relays are of the usual neutral-polar type. At east bound absolute signal 110 line relay L^{110} is provided with a neutral armature which operates neutral contact 16 also a polarized armature which operates polar contact 20. When east bound intermediate signal 112 is in either its 45° or its 90° position its pole changer N, P, will be in its normal position as shown and this will supply a current of normal or positive polarity from battery B^{112} to line wire 3, and east bound line relay L^{110} at signal 110 will be energized in its normal magnetic condition which will hold its neutral contact 16 and also polar contact 20 closed. When east bound signal 112 is in the stop position its pole changer N, P, will be reversed and this will supply a current of reverse polarity from battery B^{112} to line wire 3, and east bound line relay L^{110} at signal 110 will be energized in its reverse magnetic condition which will hold its neutral contact 16 closed and its polar contact 20 will be held open.

The motor circuits for operating the semaphore signal are of the usual type where neutral polar line relays are used. At absolute signal 110 the 45° motor circuit is from battery B^{110} , positive wire p , wire 15, neutral contact 16, wire 17, 45° motor mechanism, not shown, wire 18, negative battery, wire n , to battery B^{110} . The 90° motor circuit is the same up to neutral contact 16, from which it is by wire 19, polar

contact 20, wire 21, 90° motor mechanism, not shown, and wire 18 and negative wire n to battery B^{110} . All other motor circuits are the same. West bound motor circuits are designated by another set of numerals.

The operation of the system is as follows:—Figs. 3 and 4 show the circuits set for the east bound train A on the east bound main track approaching absolute signal 110. The switch tender having closed the switch S^{110} , the circuit controller 36 is open, and this opens the line control circuit for west bound line relay L^{113} at west bound signal 113 which is thereby put to "stop". West bound line relay L^{113} also opens its absolute contact 37 which opens the line control circuit for west bound line relay L^{115} at signal 115 in Fig. 4, which is thereby put to stop. West bound line relay L^{115} also opens its absolute contact 37 which opens the line control circuit for west bound line relay L^{117} at west bound absolute signal 117 which is thereby put to stop. Setting the switch S^{110} has thereby put all west bound signals 113, 115 and 117 to their stop position. All east bound signals 110, 112 and 114 remain clear for the east bound train A.

At west bound signal 113 line relay L^{113} by closing its back contact 11 closes the permissive control circuit which cuts out absolute contact 7 of east bound line relay L^{112} . This permissive circuit is as follows: From contact 4 of track relay R^{113} , wire 5, wire 10, back contact 11 of west bound line relay L^{113} , wire 12, circuit controller 13, now closed, signal 113 being at stop, wire 14 and wire 9 to the pole changer P, N, for battery B^{112} .

At west bound signal 115 a similar condition of line relay L^{115} and signal 115 has closed the permissive circuit and cut out the absolute contact 7 of east bound line relay L^{114} .

The absolute control east bound is now cut off at line relays L^{112} and L^{114} . The east bound control circuits now have track relay control only, the same as in ordinary single track signal systems without the absolute permissive feature. This absolute cut off action takes place in advance of the east bound train A.

While the east bound train is passing through track section T^{110} track relay R^{110} will be deenergized and while passing through track section T^{113} track relay R^{113} will be deenergized and this will put absolute signal 110 to stop. While the east bound train is passing through track section T^{112} , track relay R^{112} will be deenergized and while passing through track section T^{115} track relay R^{115} will be deenergized and this will put east bound signal 112 to stop. When the east bound train has cleared out of the foregoing track sections the several track relays, as R^{110} , R^{113} , R^{112} and R^{115} , will be

again energized in successive order, and east bound line relays L^{110} and L^{112} , will be energized. West bound line relays L^{113} and L^{115} will be deenergized and west bound signals 113 and 115 will be at stop. East bound absolute signal 110 will be at 90° and signal 112 will be at 45° as shown in Figs. 5 and 6.

Figs. 5 and 6 show the east bound train 10 A in track section T^{114} with east bound signal 112 at 45° and absolute signal 110 at 90° . Signal 112 is held at 45° by the closed back contact 11 of west bound line relay L^{115} and the closed circuit controller 15 13 of west bound signal 115 the complete circuit being as follows: East bound signal 114 being now at stop its pole changer P, N, is in its reverse position, as shown, and battery B^{114} supplies a negative current to line wire 3 as follows:—From common wire C positive pole changer P, positive wires p, p, battery B^{114} , negative wire n, negative pole changer N, wire 9, wire 14, circuit controller 13 of west bound signal 25 115, wire 12, back contact 11 of west bound line relay L^{115} , wire 10, wire 5, contact 4 of track relay R^{116} , line wire 3, contact 2 of track relay R^{112} , wire 1, east bound line relay L^{112} and common wire C back to the positive pole changer P at signal 114. This negative current will energize east bound line relay L^{112} in its reverse magnetic condition which will open its polar contact 20 and prevent the 90° motor circuit from being operated and its neutral contact 16 will hold signal 112 in its 45° position only, as shown.

The 45° position of east bound signal 112 will shift its pole changer P, N, to its normal position, as shown, and this will clear absolute signal 110 to its 90° position. The complete circuit being as follows: From common wire C at signal 112, negative pole changer N, negative wire n, battery B^{112} , positive wires p, p, positive pole changer P, wire 9, wire 8, absolute contact 7, the line relay L^{112} being now energized, wire 6, wire 5, contact 4 of track relay R^{113} , line wire 3, contact 2 of track relay R^{110} , wire 1, east bound line relay L^{110} and common wire C back to the positive pole changer P at signal 114.

At signal 113 it will be noted that the permissive circuit for signal 110 also is closed as follows:—From contact 4 of track relay R^{113} , wire 5, wire 10, back contact 11 of line relay L^{113} , wire 12, circuit controller 13 of west bound signal 113, and wires 14 and 9 to the positive pole changer P of signal 112, that is, the control circuit for signal 110 is now held closed by both the absolute contact 7 of line relay L^{112} , and also by the permissive back contact 11 of west bound control relay L^{113} and circuit controller 13 of west bound signal 113. The open condition of circuit controller 36 at switch S^{110}

holds line relay L^{113} deenergized and signal 113 at stop. A following east bound train may now be admitted to the block.

The route will be held set for east bound train movements so long as the switch S^{110} 70 remains set for admitting an east bound train to the single track section.

In Figs. 7 and 8 it is assumed that no other east bound trains are to be admitted to the single track section and the switch 75 tender has restored switch S^{110} to its normal open position which closes its circuit controller 36, and this clears west bound signals 113 and 115, the control circuits for these two signals being now normal, the 80 same as in Figs. 1 and 2.

The energized condition of west bound line relay L^{115} now opens its back contact 11 which opens the permissive control for east bound signal 112. The east bound train 85 being now in track section T^{114} and track relay R^{114} deenergized, east bound line relay L^{114} also is deenergized and its absolute contact 7 is open. The open condition of absolute contact 7 of east bound line relay L^{114} , and the open condition of permissive contact 11 of west bound line relay L^{115} and the open condition of circuit controller 13 of signal 115 now opens the circuit from battery B^{114} to east bound line relay L^{112} which 90 will be deenergized and put signal 112 to stop again, as shown.

In the same way the open condition of absolute contact 7 of east bound line relay L^{112} and the open condition of permissive contact 11 of west bound line relay L^{113} and circuit controller 13 of signal 113 opens the circuit from battery B^{112} to east bound line relay L^{110} which will be deenergized and put absolute signal 110 to stop.

From the foregoing it will be seen that in this case the east bound train being in the stretch of single track, now in track section T^{114} when the switch tender restores the switch S^{110} to its normal position west bound signals 115 and 113 are put clear and east bound signals 110 and 112 are put to stop. The signals are now in a condition to provide for a back up movement of the train A now in track section T^{114} . West 115 bound signals 115 and 113 are clear for the back up west bound movement and east bound signals 110 and 112 are at stop against an east bound movement.

While the east bound train A is in the stretch of single track, restoring the switch S^{110} to its normal position puts absolute signal 110 and signal 112 to stop and the block is closed against east bound train movements into the stretch of single track. The switch tender may, however, restore the route to its east bound condition by closing the switch S^{110} as before.

East bound signal 116 which is for the double track section is controlled in the 130

ordinary way for double track service and is not involved in any way with the invention. The clear position of signal 116 will authorize the east bound train A to proceed into the double track section T^{113} , switch S^{117} being now normal.

When the east bound train clears out of track section T^{114} track relay R^{114} will be energized and track relay R^{117} will be de-energized, and hold open the control circuit for west bound absolute signal 117, and also east bound signal 114 in the usual way. When the east bound train clears out of track section T^{117} track relay R^{117} will be energized and by closing its contact 32 will clear west bound absolute signal 117 and by closing its contact 4 will close the line circuit for east bound line relay L^{114} which will be energized by a current 20 of reverse polarity from battery B^{116} , due to the reverse position of pole changer P, N, of east bound double track signal 116, it being at stop due to the presence of the train in track section T^{116} . Signal 114 will be held at its 45° position as usual. This leaves every thing clear in the single track section, except signal 114, the same as shown in Figs. 1 and 2.

Figs. 9 and 10 show a special feature of my invention not found in other single track signal systems. In Figs. 3 and 4 as previously explained, absolute signal 110 being clear, the switch tender has set the switch S^{110} so as to permit the east bound train A approaching on the east bound main track to enter the single track. This by opening circuit controller 36 has put all west bound signals as 113, 115 and absolute signal 117 to their stop position. East bound signals 35 110, 112 and 114 remain clear. The stop position of west bound absolute signal 117 closes the block against west bound train movements. In Fig. 10 at west bound absolute signal 117 is shown one of the new features which may be termed a switching movement against opposing traffic. Assume that switch engine B now on the west bound main track is to move westward into the single track section T^{117} and then eastward 40 into main track section T^{116} . Switch indicator I^{117} is provided for this purpose and is controlled by track sections T^{117} , T^{114} , T^{115} , T^{112} and T^{113} , the control circuit being 45 as follows: From common wire C, indicator I^{117} , wire 53, contact 54 of track relay R^{117} , line wire 55, contact 56 of track relay R^{114} wire 57, contact 58 of track relay R^{115} , line wire 59, contact 60 of track relay R^{112} , wire 61, contact 62 of track relay R^{113} , wire 63, wires 38 and 39, negative pole changer N, negative wire n, battery B^{113} , positive wires p, p, and positive pole changer P to common wire C. Track sections T^{113} , T^{112} , T^{115} , T^{114} and T^{117} being now unoccupied, switch 50 indicator I^{117} is clear and this authorizes 55

the switch tender to ignore the stop indication of absolute signal 117 and set the switch S^{117} for this special switch engine movement. This movement of the switch S^{117} opens circuit controller 6 which opens 70 the control circuit for east bound line relay L^{114} and this puts east bound signal 114 to its stop position, as shown. The deenergized condition of east bound line relay L^{114} by closing its back contact 41 closes the per- 75 missive circuit for absolute signal 117 and the negative current from battery B^{116} will energize west bound line relay L^{117} in its reverse magnetic condition which will open its polar contact 50 and clear absolute signal 80 117 to its 45° position only as shown. This 45° indication of absolute signal 117 authorizes the switch engine B to enter track section T^{117} , and the main track signal 116 being clear, the switch tender will then re-store the switch S^{117} to its normal position and the switch engine B will then proceed eastward into the east bound main track T^{116} , and eastward. While this movement is being made the switch engine B will be 85 in track sections T^{117} F or T^{117} and the de-energized condition of track relay R^{117} by opening its contact 4 will hold east bound line relay L^{114} deenergized and its absolute 90 contact 7 for east bound line relay L^{112} will be open, but back contact 11 of west bound line relay L^{115} being now closed and signal 115 being at stop and its circuit controller 13 closed provides the permissive control for east bound line relay L^{112} which being ener- 95 gized by the reverse current from battery B^{114} through the reversed pole changer P, N, will hold its polar contact 20 open and hold signal 112 at its 45° position only as shown.

It will now be noted that at signals 115 and 114 both line relays L^{115} and L^{114} are deenergized. Back contact 11 of west bound line relay L^{115} gives the permissive control for east bound signal 112, and back contact 41 of east bound line relay L^{114} gives the 100 permissive control for absolute signal 117. 105

This switching movement changes signal 112 from 90° to its 45° position but does not change absolute signal 110. The east bound train A may therefore proceed to signal 112 110 where it will receive the 45° indication as shown.

In case the east bound train A had already entered track section T^{113} , deenergized track relay R^{113} by opening its contact 62 would hold switch indicator I^{117} at stop and the switch tender at absolute signal 117 would not have set the switch S^{117} for the switch engine movement.

Only one switch indicator I^{117} is shown. The switch S^{110} at east bound absolute signal 110 should also be provided with a similar switch indicator, as I^{110} , and control circuit. This has been omitted to simplify the drawings. This switch indicator I^{117} is for 125 130

no other purpose than to permit switching movements against opposing traffic and may be omitted when not needed.

In the foregoing descriptive matter it has been assumed that the main switch as S^{110} or S^{117} is operated by the switch tender. Obviously it may be operated by the trainman or by a signalman located at an interlocking station. The double track sections 10 may form part of single track passing stations in the same way as may be found in some single track roads in Europe, in which roads a train arrives at a station on its regular double track section. The invention 15 may also be applied to the lap-siding passing track arrangement in single track operation, in which separate passing tracks are used, one for each direction. It may also be applied to the third or middle track of 20 a three track road and also to any track of a multiple track road.

I claim:

1. In a railway signal system, a stretch of track divided into block sections, signals for 25 said sections, means including a line circuit and a line relay for controlling each signal, each means for controlling a number of the signals being controlled in common by the controlling means of the signals next in advance that control traffic in both directions therefrom.

2. In a railway signal system, a stretch of track divided into block sections, signals for 35 said sections, and means including a line circuit and a line relay for controlling each signal, the absolute control for each of a number of the line circuits being effected by the controlling means for another of the signals, and the permissive control by the 40 controlling means of still another signal.

3. In a railway signal system, a stretch of track divided into block sections, signals for 45 said sections, and means including a line circuit and a line relay for controlling each signal, the absolute control for each of a number of the line circuits being effected by the signal controlling means of the signal next in advance that controls traffic in the same direction, and the permissive control of the same signal by the controlling 50 means of still another signal in advance that controls traffic in the opposite direction.

4. In a railway signal system, a stretch of track divided into block sections, signals for 55 said sections, means including a line circuit and a line relay for controlling each signal, the absolute control for each of a number of the line circuits being effected by the controlling means for another of the signals, and the permissive control by the 60 controlling means of still another signal and a circuit controller included in the permissive control operative to complete the permissively controlled line circuit when said still 65 another signal is at danger, and to open it

when said still another signal is at clear or caution positions.

5. In a railway signal system, a stretch of track divided into block sections, signals for 70 controlling traffic through said sections and means including a line circuit and a line relay for controlling each signal, each of a number of the line circuits being branched, one branch constituting the absolute control and being controlled by the controlling 75 means of the signal next in advance and governing traffic in the same direction, the other branch constituting the permissive control and being controlled by the controlling means of another signal governing traffic in the opposite direction.

6. In a railway signal system, a stretch of track divided into block sections, signals for 80 controlling traffic through said sections, means including a line circuit and a line relay for controlling each signal, each of a number of the line circuits being branched, one branch constituting the absolute control and being controlled by the controlling 85 means of the signal next in advance and governing traffic in the same direction, the other branch constituting the permissive control and being controlled by the controlling means of another signal governing traffic in the opposite direction, and a circuit controller included in the permissive 90 branch of the line circuit and operative with said another signal to complete the permissive circuit when said another signal is set at danger and open the permissive circuit 95 when said another signal is in all other positions.

7. In a railway signal system, a stretch of track, signals arranged along the track and governing traffic in both directions 100 thereover, means including a line circuit and a line relay for governing each signal, said means for each intermediate signal having absolute control of the signal governing means of the signal next to the rear that 105 governs traffic in the same direction, and having permissive control of the signal governing means of the signal next in advance that governs traffic in the opposite direction.

8. In a railway signal system, a stretch of 110 track, signals arranged along the track and governing traffic in both directions thereover, means including a line circuit and a line relay for governing each signal, said means for each intermediate signal having absolute control of the signal governing 115 means of the signal next to the rear that governs traffic in the same direction, and having permissive control of the signal governing means of the signal next in advance that 120 governs traffic in the opposite direction, said permissive control including two switches in series, one operable with the signal to closed position when the signal is at danger and open when the signal is in all other positions, 125 130

and the other closed when the line relay controlling the relay is deenergized.

9. In a railway signal system, a stretch of track, signals arranged along the track and governing traffic in both directions thereover, and means including a line relay and a line circuit controlling each signal, the line relay of each intermediate signal controlling the line circuit of the signal next in advance that governs traffic in the opposite direction and also the line circuit of the signal next in the rear that governs traffic in the same direction, the line circuits controlled by each relay being opened and closed alternately as the relay is energized or deenergized in the control of its own signal.

10. In a railway signal system, a stretch of track, signals arranged along the track and governing traffic in both directions thereover, means including a line relay and a line circuit controlling each signal, the line relay of each intermediate signal controlling the line circuit of the signal next in advance that governs traffic in the opposite direction and also the line circuit of the signal next in the rear that governs traffic in the same direction, the line circuits controlled by each relay being opened and closed alternately as the relay is energized or deenergized in the control of its own signal, and track relays connected at intervals along the stretch of track and controlling the line circuits of the signals, each track relay controlling the line circuit of the adjacent signal and the line circuit of the signal next in advance that governs traffic in the opposite direction.

11. In a railway signal system, a stretch of track divided into block sections, a pair of signals at each junction of the sections and governing traffic in opposite directions therefrom, and means including a line circuit and a line relay for governing each signal, the line circuit for each signal being controlled in common by the line relays of the pair of signals at one of the block

section junctions next adjacent, one of the common controls of the line circuit being effective to close the line circuit when the controlling line relay is in one magnetic condition and the other common control being effective to close the circuit when the controlling line relay is in a different magnetic condition.

12. In a railway signal system, a stretch of track divided into block sections, a pair of signals at each junction of the sections and governing traffic in opposite directions therefrom, means including a line circuit and a neutral-polar type of line relay for governing each signal, the line circuit for each signal being controlled in common by the line relays of the pair of signals at one of the block section junctions next adjacent, one of the common controls of the line circuit being effective to close the line circuit when the controlling line relay is in one magnetic condition and the other common control being effective to close the circuit when the controlling line relay is in a different magnetic condition, and a pole changer in each line circuit and operated by the signal governing traffic in the same direction and whose line relay is one of those having a control over the line circuit.

13. In a railway signal system, a stretch of track, signals arranged along the track and governing traffic in both directions thereover, means including a normally closed line circuit and a line relay for governing each signal, said means for each intermediate signal when energized having absolute control of the signal governing means of the signal next to the rear that governs traffic in the same direction, and when deenergized having permissive control of the signal governing means of the signal next in advance that governs traffic in the opposite direction.

In witness whereof, I hereunto subscribe my signature.

ROBERT J. HEWETT.
